UNITED STATES PATENT OFFICE.

BURNS D. LOCKWOOD, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

CENTER-BEARING FOR CARS.

1,161,941.

Specification of Letters Patent. Patented Nov. 30, 1915.

Application filed December 5, 1911. Serial No. 664,099.

To all whom it may concern:

Be it known that I, BURNS D. LOCKWOOD, a citizen of the United States, residing at No. 444 Dawson avenue, Bellevue, in the county of Allegheny and State of Pennsylvania, have invented certain new and useful Improvements in Center-Bearings for Cars, of which the following is a full, clear, and exact description, such as will enable others skilled in the art to which it appertains to make and use the same, reference being had to the accompanying drawings, forming part of this specification.

This invention relates to a new and useful improvement in center bearings for railway cars the object being to provide means whereby the center bearing may be adjusted in a vertical direction relative to the underframe of the car, to compensate for wear of the center bearing, or the sagging or distortion of the end portion of the car and its underframe.

Another object of my invention is to provide means whereby the coupler head (not shown) resting in or depending from the end sill may be adjusted to substantially its normal height above the track rails, when for any reason, such as wear of journals and journal bearings, set of springs or distortion of the end of the car, the height of the coupler head above the track rails is outside the permissible limits prescribed by the safety appliance act of 1893, and amendments thereto of 1896 and 1903.

With these objects in view, the invention consists in providing the upper portion of the center bearing member with a screw thread on its cylindrical surface, such screw thread coöperating with a corresponding screw thread formed in the members of the underframe with which the center bearing member is connected.

Another feature of the invention resides in the means for locking the bearing member in its adjusted position, and still other features of the invention reside in the construction, arrangement and combination of the several parts, all as will hereinafter be described, and afterward pointed out in the claims it being understood that changes in the form, proportion, size and minor details may be made within the scope of the claims, without departing from the spirit or sacrificing any of the advantages of the invention.

In the drawings, in which similar reference characters refer to similar parts, throughout the several views, Figure 1 is a part plan view of an underframe, showing the application of my new center bearing in accordance with my invention; Fig. 2 is a part longitudinal-sectional view, the section being taken on line 2—2 of Fig. 1; Fig. 3 is an enlarged horizontal-sectional view taken on line 3—3 of Fig. 2; Fig. 4 is an enlarged cross-sectional view taken on line 4—4 of Fig. 2; Fig. 5 is an enlarged cross-sectional view taken on line 5—5 of Fig. 3, and Fig. 6 is an enlarged cross-sectional view taken on line 6—6 of Fig. 3.

1 indicates the center sill, which for the purpose of illustration is shown of the single structural type, and composed of a web plate 2, compression angle bars 3 and 4, and tension angle-bars 5 and 6 all secured to the web plate 2.

7 and 8 indicates the two component members of the body bolster the main body portions of which are shown of substantially I section, it being understood that they may be made of any preferred form to suit the type of underframe and trucks which it is contemplated to use. They are furnished with side bearings 9, 9, and means 10, 10 for supporting the side sills, 11, 11. The ends of the bolster members adjacent to the center sill, are provided with extensions 12, 12 at substantially right angles to their main body, adapted to contact with and be secured to the end portions 13 of the center sill web plate 2. These extension portions of the bolster members are further provided with suitable flanges 14, 14, adapted to contact with, and be secured to, the horizontal flanges of the compression angle bars 3, 4 and tension angle bars 5, 6, as shown in Fig. 5.

The portion 15 of the body bolster members, intermediate the main body portion and the flange portions 12, 12, is disposed at an angle of substantially forty five degrees, for a purpose hereinafter referred to and described in detail.

16, 16 indicates the draft sills which for the purpose of illustration are shown as being made in one piece, the ends nearest to the bolster being connected by the portions 17, 17, forming connecting webs between the two draft sills. These draft sills are shown of channel section, but may be made of any other suitable section, to comply with va-

rious conditions existing in the underframe of the car. For the purpose of securing the draft sill member to the bolster members, the latter are each provided with an extension member 18, 18, extending substantially in the direction of the longitudinal center line of the car, parallel and in contact with the web portions 19, 19 of the draft sills, and adapted to be secured to each other as shown in Fig. 3. The draft sill member is further provided with upper and lower flanges, 20 and 21, which are adapted to contact with and be secured to corresponding flanges 22, 23 on the bolster extension members 18, 18.

The end 24 of the draft sill member 16, next to the bolster, is shaped or beveled to correspond with the angle of the intermediate portions 15, of the body bolster members 20 above referred to, and as an additional means to secure the draft sill members and body bolster members together, substantial bolts 25 are passed through suitable holes provided in said members, thus connecting these members together in a substantial and practical manner. For the purpose of receiving the center bearing, the end portion of the draft sill member and the intermediate portions of the bolster members are shaped so that they form when secured together a cylindrical opening 26, the portions forming such cylindrical opening being provided with spiral projections 40, which are, in effect, a female screw thread.

85 The center bearing member shown in vertical section in Figs. 2 and 4, consists of the bearing member 27 which may be of any preferred form and contour, and an upwardly extending or stem portion 28. The stem portion 28 is shown of hollow cylindrical form to reduce its weight and admit of the insertion of the king pin, and is provided on its outer surface with a spiral projection 41, which forms in effect a screw thread of size, proportions and pitch corresponding to that provided in the cylindrical opening 26, formed by the end portions of the draft sill 16 and body bolster members 7 and 8. Holes 29 are provided in the stem portion of the center bearing member to permit of the insertion of a bar or other suitable tool for the purpose of revolving the center bearing member on its vertical axis, when for any reason it is desired to change the height of the underframe relative to the lower face 30, of the center bearing member, by screwing the stem of the said member farther into the opening to lower the underframe, or vice versa to raise the underframe, 60 the weight of the car body and underframe, on the lower or truck center bearing, being first relieved by jacks or other suitable means.

65 For the purpose of preventing accidental rotation of the center bearing in its screw

socket and locking the stem of the center bearing member in the desired vertical position relative to the underframe, a slot 31 is provided in the end portion of the draft sill member through which a locking member 32 70 may be passed, one end of the locking member being adapted to engage with vertical slots 33, which are provided in the screw thread portion of the stem of the bearing member, the other end of the locking member 75 being secured by a machine screw or other suitable means to the lower horizontal flange 34 of the draft sill member. It is to be understood the locking member 32, may be arranged to pass through a slot in the 80 portion 15 of the draft sills, in which case it would be secured to one of the horizontal flanges with which portion 15 is provided.

85 indicates the end sill which may be of any preferred construction, but which is shown in the drawings as being formed of a rolled channel, reinforced by an angle bar 36. Gusset plates, 37, 37 are secured to the lower flanges of the bolster and draft sills, and gusset plates 38, 38 are secured to the 90 lower flanges of the side sills and end sills, the end portion of the underframe being braced against deformation by the diagonal braces 39, 39, extending from gusset plate 37 to gusset plates 38, at each corner of the 95 underframe.

Having thus described my invention, what I claim and desire to secure by Letters Patent is:—

1. In a car underframe, the combination 100 with a center bearing member, of means integral with said underframe and means integral with said center bearing member adapted to engage the first mentioned means to provide a vertical adjustment of said center bearing member relative to said underframe.

2. In a car underframe, the combination with a center sill and draft sills, of a body bolster having ends extending in one direction to engage with and be secured to said center sill, and having ends extending in an opposite direction to engage with and be secured to the draft sills, the adjacent ends of said bolster and draft sills forming a cylindrical aperture, a screw thread formed in said aperture, a center bearing having an upper portion, a screw thread on said upper portion adapted to cooperate with the screw thread in said aperture.

3. In a car underframe, the combination with a center sill and draft sills, of a body bolster having ends extending in one direction to engage with and be secured to said center sill, and having ends extending in an opposite direction to engage with and be secured to the draft sills, the adjacent ends of said bolster and draft sills forming a cylindrical aperture, a screw thread formed in said aperture, a center bearing having an 125

upper portion, a screw thread on said upper portion adapted to coöperate with the screw thread in said aperture, to provide a vertical adjustment of the underframe relative to the center bearing.

4. In a car underframe, the combination with draft sills of a center sill terminating between the bolsters, bolsters, the rear ends of which bend toward and lap past the ends of said center sill, and the front ends of said bolster bend toward and lap past the ends of the draft sills, a cylindrical aperture formed by the adjacent ends of the bolster and draft

sills, a screw thread formed in said cylindrical aperture, a center bearing member having an upper portion, a screw thread formed on said upper portion adapted to coöperate with the screw thread in said aperture to provide a vertical adjustment of the underframe relative to the center bearing.

In testimony whereof I affix my signature in presence of two witnesses.

BURNS D. LOCKWOOD.
